MIXER

Charles V. Russell, Miles City, Mont.

Application September 21, 1939, Serial No. 295,951

4 Claims. (Cl. 259—7)

This invention relates to mixers of the class especially adapted for mixing solid materials of different kinds and with a liquid binder, and has for the primary object the provision of a device of this character wherein the materials will be caused to travel therethrough by gravitation, receiving a thorough mixing during the travel thereof and which permits the device to operate by less power and with a less number of parts.

Another object of this invention is the provision of a device of this character which will be readily accessible for making repairs and adjustments and which may be heated if desired.

With these and other objects in view, the invention consists in certain novel features of construction, combination and arrangement of parts to be hereinafter more fully described and claimed.

For a complete understanding of my invention, reference is to be had to the following description and accompanying drawings, in which

Figure 1 is a vertical sectional view illustrating a mixer constructed in accordance with my invention.

Figure 2 is a top plan view illustrating the same.

Figure 3 is a fragmentary perspective view showing one of the connections between a sweep or blade and a disc of the device.

Figure 4 is a fragmentary perspective view illustrating an adjustable hinged type mounting used in the mounting of the sweep or blade.

Figure 5 is a detail sectional view taken on the line 5—5 of Figure 1.

Referring in detail to the drawings, the numeral 5 indicates a vertically arranged cylindrical drum composed of companion sections equipped with barrels 6 through which extend removable tie rods 7 whereby the sections of the drum may be readily taken apart or detached for hinging movement relative to each other.

The lower end of the drum is equipped with a sectional discharge throat 8, the sections of which are secured on the sections of the drum.

The throat 8 supports centrally of the lower end of the drum a bearing 9 while a bearing 10 is supported centrally of the drum at the upper end of the latter by a spider 11 detachably secured onto the walls of the drum by stud bolts 12. The bearings 9 and 10 rotatably support a shaft 13 which is of rectangular shape in cross section at certain portions thereof which have a driving fit with spacer blocks 14 mounted thereon. Power is applied to the shaft 13 in any well known manner.

The ends of the spacer blocks have interfitting connections with each other and clamp therebetween rotatable plates or discs 15 adapted to rotate with the shaft 13 and have their peripheries spaced from the walls of the drum. Each plate 15 is convex so that material falling thereon will slide in the direction of the walls of the drum.

Fixed plates or discs 16 are mounted on the walls of the drum and are arranged between the rotatable discs or plates and spaced an equal distance therefrom and are provided with centrally arranged openings 17 through which the spacer blocks 14 pass freely and also provide passageways for the material of said plates or discs 16 to 15 gravitate therefrom centrally of the drum onto the plates or discs 15 thereunder. The plates or discs 16 are concaved so as to slope toward the center of the drum while the discs or plates 15 slope toward the walls of the drum. Therefore, 20 it will be seen that said plates 15 and 16 coact in bringing about an irregular passage of materials through the drum aided by gravitation. The plates or discs 16 are of sectional formation with the sections thereof secured onto the sections of the drum and have secured to their under faces semi-circular reinforcing bands 18. The bands which are secured to one section underlie and engage with the adjacent section thereby coacting in maintaining the sections of the plates or 25 discs 16 in proper alignment and still permit separation of the sections of the discs or plates 16 with the separation of the sections of the drum.

Arranged within the drum are fixed and rotatable sweeps or blades 19 and 20 each being arcuately curved from end to end and provided with scraping edges for coaction with the plates or discs 15 and 16, it being understood that the blades or sweeps have wiping contact with said plates or discs, the fixed blades or sweeps coacting with the rotatable discs or plates while the rotatable blades or sweeps coact with the fixed plates or discs.

The fixed blades or sweeps are hingedly connected to mountings 21 adjustably secured on the walls of the drum 5 for vertical adjustment. The rotatable blades or sweeps are similarly mounted on the spacer blocks 14 for rotation therewith. Adjustable tie means 22 are provided 45 between the fixed blades or sweeps and the fixed plates or discs thereover and similar adjustable tie means is provided between the rotatable sweeps and the rotatable discs or blades. The adjustable tie means may be readily adjusted cir- 50 55

cumferentially of the discs or plates for the purpose of varying the radial pitch of the blades or sweeps and also permits the blades or sweeps to be adjusted toward and from the discs or plates 5 for varying their wiping action thereon.

It is to be understood that the aggregate and liquid fluid is fed into the upper end of the drum onto the uppermost rotating disc or plate and is contacted by the uppermost sweeps or blades 10 which are non-rotatable causing said material to be swept from the uppermost disc or plate and toward the walls of the drum for depositing onto the fixed plate or disc thereunder and is swept inwardly of the latter by the rotating sweeps or 15 blades, consequently bringing about a zig-zag passage of the material through the drum under gravitation receiving a thorough mixing so that on reaching the discharge throat 8 the solid and liquid material will be efficiently combined with 20 the least expenditure of motive power and manual labor.

The lowermost spacer block is mounted on a plate 23 which rides on rollers 24 carried by a fixed support 25. The fixed support, rollers and 25 plate 23 form a turntable arrangement.

An outer jacket 26 is provided for the drum which also is of sectional formation, the purpose of which is to permit heat to be injected therein for the heating of the materials as they pass 30 through the drum and during the time of receiving the mixing action.

In use, it is proposed that several units of the character described in connection with the showing made in Figure 1 may be so arranged that 35 the materials discharged from one unit may be conveyed into the adjacent unit so that on the completion of travel of the materials through all of the units said materials then will be in a very highly mixed state ready for efficient use and further it is to be understood that the unit first 40 receiving the materials may be used as a hydrater by injecting heat into the sockets thereof and eliminating the injection of the liquid binder so that the solid material passing through the first unit will be freed of any moisture contents, it being understood that as the dried materials pass through the remaining units they 45 will be mixed with the liquid binder.

It is believed that the foregoing description when taken in connection with the drawings will 50 fully set forth the construction and advantages of this invention to those skilled in the art to which such a device relates, so that further detailed description will not be required.

Having thus described my invention, what I 55 claim is:

1. In a device of the character described, a vertically arranged drum adapted to have materials pass therethrough by gravitation, substantially cone-shaped discs arranged in and secured on said drum with the concaved faces thereof disposed uppermost and each having a centrally arranged opening, a power shaft extending through said openings, substantially cone-shaped discs secured to said shaft and arranged above and spaced from the fixed discs and having the convex faces thereof disposed uppermost and the peripheries thereof spaced from

the walls of the drum, and sweeps coacting with said discs.

2. In a device of the character described, a sectional vertically arranged drum adapted to have materials pass therethrough by gravitation, means for detachably connecting the sections of the drum, sectional substantially cone-shaped discs fixed in said drum with the concaved faces thereof disposed uppermost and each having a centrally arranged opening, a power shaft extending through said openings, rotatable substantially cone-shaped discs secured to said shaft and arranged above and spaced from the fixed discs and having the convex faces thereof disposed uppermost and the peripheries thereof spaced from the walls of the drum, fixed sweeps coacting with the rotatable discs, and rotatable sweeps secured to said shaft and coacting with the fixed discs.

3. In a device of the character described, a 20 sectional vertically arranged drum adapted to have materials pass therethrough by gravitation, means for detachably connecting the sections of the drum, sectional substantially cone-shaped discs fixed on and arranged in said drum 25 with the concaved faces thereof disposed uppermost and each having a centrally arranged opening, a power shaft extending through said openings, rotatable substantially cone-shaped discs secured to said shaft and arranged above and 30 spaced from the fixed discs and having the convex faces thereof disposed uppermost and the peripheries thereof spaced from the walls of the drum, non-rotatable sweeps hingedly and adjustably mounted on the drum and having wiping 35 contact with the rotatable discs, rotatable sweeps hingedly and adjustably mounted on the shaft and having wiping contact with the fixed discs, adjustable tie means connecting the non-rotatable sweeps to the non-rotatable discs, and 40 adjustable tie means connecting the rotatable sweeps with the rotatable discs.

4. In a device of the character described, a sectional vertically arranged drum adapted to have materials pass therethrough by gravitation, 45 means for detachably connecting the sections of the drum, sectional substantially cone-shaped discs fixed on and arranged in said drum with the concaved faces thereof disposed uppermost and each having a centrally arranged opening, a power shaft extending through said openings, rotatable substantially cone-shaped discs secured to said shaft and arranged above and spaced from the fixed discs and having the convex faces 50 thereof disposed uppermost and the peripheries thereof spaced from the walls of the drum, fixed sweeps hingedly and adjustably mounted on the drum for coaction with the rotatable discs, rotatable sweeps hingedly and adjustably mounted on the shaft for coaction with the fixed discs, 55 adjustable tie means connecting the fixed sweeps to the rotatable discs, adjustable tie means connecting the rotatable sweeps with the rotatable discs, each of said sweeps being of elongated formation and arcuately curved from end to 60 end and having a scraping edge.

CHARLES V. RUSSELL.
